UNITED STATES PATENT OFFICE

THOMAS FRANKLIN DALTON, OF FLAT RIVER, MISSOURI

MANUFACTURE OF DECORATIVE PANELS

Application filed November 7, 1930. Serial No. 494,157.

The object of this invention is to provide an inexpensive ornamental sheet which may be employed for decorating cabinets of various kinds or which may be formed into ornamental objects. The invention also has for its object the production of such a sheet or panel in an inexpensive manner. The invention is illustrated in the accompanying drawings and will be hereinafter fully set forth and defined.

In the annexed drawings:

Figure 1 is a plan view of a panel constructed in accordance with my invention,

Fig. 2 is a transverse section showing the panel in the first stage of its development,

Fig. 3 is a similar view showing a second stage in the development of the panel, and

Fig. 4 is a similar section of the completed panel.

In the practice of the present invention, I employ a glass slab 1 which may be of any convenient or desired dimensions. Preferably, the slab is fitted in a frame 2 and this frame serves as a gage for determining the height of the composition layer which is subsequently applied to the glass slab. The glass slab having been thoroughly cleaned, a coating of varnish, glue or shellac, which may be clear or contain some color as preferred, is applied to the entire surface of the slab and pieces of broken pearls, indicated at 3, are scattered over the slab so as to be embedded in the varnish and be firmly held by the same when it has dried. After the broken pearls have been placed upon the slab so as to cover the entire surface of the same as closely as possible, chips of ground pearls and finely ground colored glass, indicated at 4, are sifted onto the slab so as to fill the spaces between the pearls as completely as can be done, and finely comminuted particles of lead may be deposited at random over the varnish. The slab is then set aside until the varnish has completely set which generally will require but a few hours, and after the varnish has set I take a thin cement mixture and cover the entire area of the slab over the pearls and crushed pearl chips and colored glass, as shown at 5 in Fig. 4, the surface of the cement being made smooth and even by

the use of a trowel so that it will retain the colored elements in place but will not add any very great weight to the article. The result of this process is the production of a very highly colored and ornamental slab 55 or panel as viewed through the glass slab having an appearance similar to very closely set mosaic. The pearls possess a variety of colors which will show through the glass slab. The article produced by my process 60 may be applied to door panels and for this purpose the frame in which the glass slab is fitted may be the frame of the door panel. To complete a door panel, a second slab is covered with the pearls, colored glass and 65 cement and before the cement is entirely set the two cement surfaces are placed together and then held in firm smooth contact until set by weights placed upon the upper glass plate. The composition may be placed within 70 a mold of some transparent material and when it has set within the mold a very ornamental decorative object will be produced which may be utilized as a paper weight or otherwise. The several ingredients may be 75 arranged to represent flowers or other designs and an infinite variety of effects may be obtained.

The elements which enter into my composition are not costly and the process may be 80 practiced successfully without involving great expense so that a very desirable decorative sheet or panel may be produced cheaply.

Having thus described the invention, I 85 claim:

A decorative panel comprising a transparent slab, an adhesive coating covering the entire area of one face of the slab, colored broken pearls scattered over the surface of the slab to be embedded in the adhesive coating, ground colored glass and ground pearl chips filling the interstices between the broken pearls, finely comminuted particles of lead disposed upon the coating, and a sealing binder applied over the pearls and the 90 broken pearl chips and colored glass and having a smooth even surface.

In testimony whereof I affix my signature.
